CARTON

Lawrence W. Reaume, Monroe, Mich., assignor
to River Raisin Paper Company, Monroe,
Mich., a corporation of Michigan

Application October 24, 1936, Serial No. 107,330

3 Claims. (Cl. 229—6)

The invention relates to cartons and particularly those of the type used for transporting beverage bottles.

In the past cartons of the type mentioned have been made of cardboard and the like, which material has the advantage of reduced cost and a considerable saving in weight over previously used wooden cases. However, such cardboard cartons have the disadvantage that they are lacking in strength, and hence are apt to be crushed when a number of filled cartons are stacked one upon another, or injured during handling because of the weight of the contents. Accordingly it is the general object of the present invention to provide an improved composite cardboard and metal carton, in which the sheet metal portions are so arranged as to materially strengthen the carton without materially increasing its cost.

A further object of the invention is to provide a composite cardboard sheet metal carton in which the cardboard portions may be readily replaced as they wear.

Other objects and advantages of the invention will become apparent from the following specification, the accompanying drawing, and the appended claims.

In the drawing wherein like numerals are applied to like parts in several views;

Fig. 1 is a perspective view of the carton in a partially closed condition.

Fig. 2 is a horizontal section taken along the line 2—2 of Fig. 1.

Fig. 3 is a longitudinal section taken on the line 3—3 of Fig. 1.

Fig. 4 is a longitudinal section similar to Fig. 3 but of a modified form of the invention.

Referring to the drawing, the main body of the carton is formed of a substantially rectangular blank of cardboard, or the like, such as commonly used in the manufacture of cartons. The blank is provided with a plurality of parallel crease lines which divide it from end to end into a top flap 11, a half top member 12, a side panel 13, a bottom member 14, a second side panel 15, a second half top member 16, and a second top flap member 17 of the carton. It will be observed that these portions constitute the entire carton with the exception of the end members, and that they are formed of a single substantially rectangular sheet of material, thus avoiding waste and providing an exceedingly simple means for forming a carton.

The carton is completed by a pair of identical end members or walls 18, only one of which will be described in detail. Each end wall 18 is pro-

vided with a pair of side channels indicated generally at 19 and 20, and a bottom channel indicated generally at 21. The channels 19, 20 and 21 are substantially identical to each other and as shown best in Figs. 2 and 3 comprise an outwardly extending flange 22 integral with the main body portion of the end member 18 which forms the inner side of the channel. The material of the end member is then turned outwardly at 23 to form a bottom for the channel and thence inwardly at 24 to form the outer side of the channel, thus providing an inwardly opening channel adapted to receive the ends of the side and bottom walls of the blank 10. The channels are so formed that the end member 18 may be assembled with the remainder of the carton by simply sliding the ends of the side and bottom walls into the channels 19, 20 and 21.

In addition to the side and bottom channels the end members 18 are provided with top reinforcing channels 25 which are similar to the side and bottom channels previously described. It will be noted that the side walls 13 and 15 extend outwardly of the upper end of channels 19 and 20 through openings or gaps 26 at the upper ends of the top and side channels, and that the half top members 12 and 16 when in closed position overlie the outer surface of the top channel 25. The top flaps 11 and 17 are shorter than the half top members and are adapted to project into the interior of the carton between the end members 18 when the top is closed. Preferably the proportions of the parts are so chosen that there will be sufficient friction between the end members 18 and the edges of the top flaps 11 and 17 to hold the top members in closed position.

After the end members 18 are assembled with respect to the side and bottom walls of the container, a plurality of longitudinal and transverse partition members 31 and 32, respectively, are positioned within the box to divide it into a plurality of bottle-receiving sections. These partition members are interlocked together in the usual manner to provide a honeycomb arrangement, and end pieces 33 are provided to prevent contact between the bottles and the sheet metal end members 18. After the end members 18 are assembled and the honeycomb partition members 31, 32 and 33 are placed in position, a bolt 28 is inserted through aligned holes in the end members 18. The bolt 28 is provided with a head 29 and a nut 30 for retaining the end members against accidental displacement from the container. It is apparent, however, that when desired, the nut can be removed and the blank 10 released from

the channels 19, 20 and 21 of the end members.

In Fig. 4 is shown a modified means for securing the end members in position. In this form of the invention the structure of the container is the same in every respect with that previously described except that the end members are provided with inwardly extending perforated tongues 41 and a rod 42 having downwardly extending end portions 43 is inserted within the box with the end portions 43 received within the perforations of the tongues 41. The bent-over end portions 43 of the rod 42 are preferably bent slightly more than 90° from the axis of the rod in order that they will have to be bent apart slightly to be inserted within the apertures. This prevents accidental displacement of the rod without interfering with its removal when such is desired.

It is apparent that in accordance with the present invention there is provided an exceedingly inexpensive carton which is of great strength. In use these cartons are frequently stacked one upon the other to a relatively great height with the result that considerable pressure is applied upon the lower cartons. In the present invention this weight is sustained entirely by the sheet metal end members which are of sufficient strength to withstand relative heavy loads and thus the weaker card board sections are protected from injury. In addition the form of the end members is such that they are materially reinforced by the channel members and the channel members being extended outwardly of the box provide a suitable means by which the box may be lifted. Thus the box can be readily lifted by placing the fingers beneath the uppermost channels of the end members, and this can be done regardless of the position of the box. The upper channel 25 is of course not necessary but it is preferably provided to reinforce the end members and to provide means for lifting the container. If desired a suitable hand hole may be provided immediately below the central portion of the top channel 25 but such is not necessary as the channel itself provides sufficient means for engagement by the hand of one who is desirous of lifting the container. When the card board portions of the carton become worn or injured they may be replaced without any difficulty.

While only two forms of the invention are dis-

closed herein, it will be understood that other modifications may be indulged in within the spirit of the invention as set forth in the above specification, and as illustrated in the drawing, and within the scope of the appended claims.

What I claim is:

1. A composite carton comprising card board side and bottom walls, and a pair of sheet metal end wall members having peripheral channels adapted to receive the ends of said side and bottom walls, said end wall members having inwardly projecting perforated ears formed thereon inwardly of the channels, and a tension rod having bent-over end portions inserted in said apertures for releasably holding the end wall members in position.

2. A composite carton comprising a pair of sheet metal end members each having peripheral channels formed at the four sides thereof, said channels opening in a direction perpendicular to the plane of the end member and having their side walls projecting in the opposite direction from said plane, a bottom wall having its ends received in said channels at the lower edge of the respective end members, cardboard side walls having their ends received in the channels at the sides of the end members, a cardboard top member integral with one side member and adapted to swing into contact with the outer sides of said channels at the top of said end members, respectively.

3. A composite carton comprising a pair of sheet metal end members each having peripheral channels formed at the four sides thereof, said channels opening in a direction perpendicular to the plane of the end member and having their side walls projecting in the opposite direction from said plane, a bottom wall having its ends received in said channels at the lower edge of the respective end members, cardboard side walls having their ends received in the channels at the sides of the end members, means urging said end members toward each other, a cardboard top member integral with one side member and a tab on said top wall adapted to extend into the carton when the top is closed and to fit snugly between the end members for maintaining the lid closed.
